UNITED STATES PATENT OFFICE.

ALEXANDER G. McADIE, OF MILTON, MASSACHUSETTS.

PSYCHROMETER.

Application filed July 19, 1920. Serial No. 397,205.

To all whom it may concern:

Be it known that I, ALEXANDER GEORGE McADIE, a citizen of the United States, and a resident of Milton, in the county of Norfolk and State of Massachusetts, have invented certain new and useful Improvements in Psychrometers, of which the following is a specification.

My invention relates to psychrometers, and a purpose of my invention is the provision of an instrument of this character which quickly and accurately determines the relative and absolute humidities of the atmosphere and the dew-point or temperature at which condensation would occur.

I will describe one form of psychrometer embodying my invention and will then point out the novel features thereof in claims.

In the accompanying drawings:

Figure 1 is a view showing in side elevation one form of psychrometer embodying my invention.

Figure 2 is an enlarged fragmentary detailed view showing one of the thermometers.

Figure 3 is a fragmentary view showing in edge elevation the instrument shown in the preceding views.

Figure 4 is a fragmentary view showing in side elevation the other thermometer arranged at the opposite side of the rod from the first thermometer.

Figure 5 is an enlarged detail view showing in side elevation the cage shown in the preceding views with the lining partly removed.

Figure 6 is a view showing in bottom end elevation the cage shown in Figure 5.

Figure 7 is a transverse sectional view taken on the line 7—7 of Figure 2, and

Figure 8 is a detail view of the counter.

Similar reference characters refer to similar parts in each of the several views.

Referring specifically to the drawings and particularly to Figure 1, R designates a flat rod formed of any suitable material such as wood or aluminum and preferably of 102 centimeters in length. This rod R is capable of being bodily rotated about its upper end 50 as a center by means of a handle H rotatably mounted upon a shaft S. The shaft S is associated with a registering counter designated generally at K, such counter being of conventional form and including a graduated dial 15 and a pin 16, the latter being

adapted to engage and actuate a tapper 17 of the bell 18.

The shaft 1 of the handle H has a worm 2 which meshes with and drives the disk or dial 15 when the rod R is swung by means of the handle. The disk 15 has 100 teeth on the periphery; upon making the 99th turn of the rod the pin 16 will come into engagement with the tapper rod 3. The 100th turn causes the release of said rod so that the tapper 17 (Fig. 1) strikes the bell 18. A light spring 4 attached to the rod 3 gives the necessary tension.

As shown in Figures 1, 2 and 3, thermometers T and T' are carried by the rod R and are capable of longitudinal adjustment thereon by means of rectangular shaped yokes Y which are fixed to the thermometers and slidably embrace the rod so that when set screws W carried by the yokes 75 are moved into engagement with the rod, a locking of the thermometers T and T' in any adjusted position on the rod can be readily effected.

The thermometer T which I term the wet thermometer, is of conventional form with the exception that its face is provided with specially compiled graduated scales designated at B and B'. The scale B constitutes a list of temperatures expressed in kilograd 85 and ranging in the present instance from 900 to 1200 in multiples of 10. The scale B' is a list of pressures of water-vapor saturation equivalent to the corresponding number of kilograd, such pressures being expressed in units of force or kilobars and ranging in number in the present instance from 1 to 130.

The thermometer T', which I term the dry thermometer, is similar in construction 95 to the wet thermometer T and is provided with a temperature scale B also expressed in kilograd. The thermometer T' is provided with another scale designated at B² which comprises equivalent saturation 100 weights expressed in grams per cubic centimeter of space. These scales B and B² are of the desired range to secure the necessary comparative readings between the thermometer T' and the thermometer T.

As shown in Figures 2 and 3, the bulb of the thermometer T carries a cage designated at G which is formed of foraminous material such as wire screen. As shown in Figure 5, the upper end of the cage G is 110

provided with a tie wire 19 for securely attaching the cage to the bar. As shown in Figure 6, the lowest end of the cage G is inturned to provide an upwardly extending lip 20 which is designed for the purpose of securing an absorbent lining L therein, such lining being preferably formed of clean linen free from starch or sizing.

The cage serves to hold the linen from the thermometer bulb, the tendency of the cage being to expand linearly when the instrument is in use, and thus obviate compressional force on the bulb. This feature is of especial value when making a frost test, for at such time the wet linen would freeze to the bulb and cause an erroneous reading, were it not for the supporting cage. In expanding linearly the cage G expands both longitudinally and circumferentially so as to keep the wet lining far enough away from the bulb to prevent freezing thereto.

In operation, the cage G together with the lining L is removed from the bulb of the wet thermometer T and dipped into water until the lining is saturated. It is then slipped on the bulb and fastened by the tie wire 19. The readings of the two thermometers are now noted whereupon any desired ventilation by means of rotation is effected by swinging the rod R about the shaft S as a center. This may be readily accomplished by the operator gripping the handle H and giving a circular motion to the hand. With the rotation of the rod R a similar movement of the two thermometers T and T' is likewise effected, and with the latter adjusted to predetermined positions upon the rod, it will be clear that by rotating the rod at a predetermined speed a definite wind velocity is automatically generated, and the beginning and ending of the movement of the air over the lining L is rendered definite. The rod R can be swung either vertically or horizontally at any desired speed, such speed being determined by the registering counter K. In the present instance, the construction and operation of the counter K is such that at the completion of every 100 revolutions of the rod, the pin 16 engages the tapper 17 so as to effect a sounding of the bell 18. The wind velocity is determined by the distance of the thermometers from the top of the rod or axis of rotation. Thus at a distance of 1 metre or 39.3 inches, the thermometers when whirled will travel in one complete revolution 3.3 metres or approximately twenty feet. It is then only necessary to know the number of rotations and the time, to calculate the speed of the wind. It is found that with a little practice a normal rate of swinging of 100 revolutions per minute can be obtained. If desired, a watch may be used and the number of seconds counted.

To determine the relative and absolute

humidities and the temperature of saturation or the so-called dew-point, I employ the following equation:

$$p_s = p_e - pC (T - T_e)$$

79

in which p_s is the pressure of the water vapor at saturation or dew-point, p_e the pressure at evaporation, p the pressure of the atmosphere expressed in kilobars (1000 dynes or units of force), C a constant, T the temperature of the dry bulb expressed in kilograd (thermometry: 1000 degrees), and T_e the temperature of the wet bulb.

When the wind velocity exceeds 2 metres per second or 5 miles per hour, pC may be written as 0.18; and for purposes of quick calculation I regard it as 20% without materially effecting the results. Because of this formula one can quickly determine the relative humidity by simply referring to the values in kilobars as given for different kilograd. To calculate the relative humidity after the proper period of whirling, one reads the temperature of the wet bulb in kilograd and the corresponding pressure in kilobars. From this is subtracted 20% of the difference between the temperature reading of the two thermometers, and the relative humidity is the ratio of this value in kilobars to the kilobars opposite the dry temperature or reading of the thermometer T'. 95

The dew point or temperature of saturation is the kilograd reading opposite the numerator of the fraction giving the relative humidity. The absolute humidity is the kilogram reading on the scale B² opposite to the reading on the scale B of the thermometer T'. When calculating the absolute humidity in a room, this reading is multiplied by the cubic metres of space in the room, 105 thus giving the direct weight of the air which must be evaporated in such space and at the particular temperature then prevalent to produce saturation. The difference between the amount actually present and the amount needed for saturation gives the saturation deficit.

The instrument with some refinement can be used to measure the work done in evaporation, since this is directly proportional to the temperature. In forecasting frost, this instrument can be further used as a kata-thermometer which is an instrument used by physicians for measuring the cooling properties of the skin. A duplicate cage G is 115 warmed to any desired temperature and slipped on the bulb of the dry thermometer T'. The rate of fall is then noted. Thus two cooling rates are available; one due to evaporation with a definite wind; and another due to radiation and convection with the same definite wind. These rates are helpful in estimating the probable minimum temperature.

Although I have herein shown and de- 130

scribed only one form of psychrometer, it is to be understood that various changes and modifications that may be made herein without departing from the spirit of the invention and the spirit and scope of the appended claims.

What I claim is:

1. A psychrometer comprising a rod, means whereby said rod is supported for rotary movement about a transverse axis, a registering counter associated with the rod, dry and wet thermometers, and means whereby said thermometers are mounted for adjustment longitudinally on said rod.
- 15 2. A psychrometer comprising a rod, means whereby said rod is supported for rotary movement about a transverse axis, a registering counter associated with the rod, dry and wet thermometers, means whereby said thermometers are mounted for adjustment longitudinally on said rod, the wet thermometer having a temperature scale expressed in kilograds and a pressure scale expressed in kilobars, and the dry thermom-
20 eter having a temperature scale expressed in kilograds and an equivalent saturation weight scale expressed in grams per cubic metre of space.
- 25 3. A psychrometer comprising a rod, means whereby said rod is supported at one end for rotation about a transverse axis, a pair of yokes longitudinally adjustable on said rod, dry and wet thermometers carried by said yokes, the wet thermometer includ-
30 ing a foraminous cage, and an absorbent lining within said cage and surrounding the bulb of said thermometer.
- 35 4. A psychrometer comprising a rod, means whereby said rod is mounted for rotary movement about a transverse axis, and dry and wet thermometers adjustable longitudinally on said rod.
- 40 5. A psychrometer comprising a shaft, a rod having means for rotatably mounting it on the shaft, a registering counter, gearing incorporated in said rotatable mounting for registering the number of revolutions of said rod when a circular swinging motion is imparted to the shaft, an audible signal
45 associated with the counter, wet and dry thermometers carried by the rod, and means whereby said thermometers are mounted for adjustment longitudinally on said rod.
- 50 6. In a psychrometer, a thermometer, a foraminous cage surrounding the bulb of the thermometer, and a lining within the cage formed of absorbent material, the cage
55 expanding linearly and thus obviating com-

pressional force on the thermometer bulb.

7. In a psychrometer, a thermometer, a foraminous cage surrounding the bulb of the thermometer, a tie wire carried by the cage for securing the cage to the bulb, a lining within the cage formed of absorbent material, and a lip on the cage for supporting the lining in the cage.

8. A psychrometer comprising a rod, means whereby said rod is supported for rotary movement about a transverse axis, a registering counter associated with the rod, dry and wet thermometers, means whereby said thermometers are mounted for adjustment longitudinally on said rod, the wet thermometer having a temperature scale and a pressure scale, and the dry thermometer having a temperature scale and an equivalent saturation weight scale.

9. A psychrometer comprising a wet bulb, means by which said bulb may be whirled and means for regulating the velocity of air over the bulb in a whirling operation.

10. A psychrometer comprising a rod, a handle, means by which the rod is revolvably connected to the handle so that the rod may be rotated around the handle, a thermometer carried by the rod, means permitting adjustment of the thermometer between the end of the rod and the axis of rotation at the handle to thereby vary the velocity of an equivalent wind passing the thermometer and means to sound an alarm at a predetermined number of rotations of the rod to indicate the time of said rotation.

11. A psychrometer comprising a rod, a handle having a shaft upon which the rod is revolvably mounted so as to be rotated around the axis of the handle, a thermometer carried by the rod, a foraminous cage carrying an absorbent lining adapted to be dipped in water and thus contain a predetermined amount, means by which the cage is readily attached and detached from the bulb of the thermometer, means by which the thermometer may be adjusted along the rod between the end thereof and the axis of the handle and thus vary the velocity of the equivalent wind passing the wet lining, and means associated with the rod and handle for sounding an alarm after a predetermined time of rotation of the rod.

12. A psychrometer comprising means to be whirled, a wet bulb carried thereby, and means to vary the radial position of the bulb and thereby control the amount of air passing thereover.

ALEXANDER G. McADIE.
